UNITED STATES PATENT OFFICE.

PAUL O. UNGER, OF SYRACUSE, NEW YORK, ASSIGNOR TO MCMILLAN BOOK COMPANY, OF SYRACUSE, NEW YORK, A CORPORATION OF NEW YORK.

LEAF FLIPPER.

Application filed October 13, 1928. Serial No. 312,259.

This invention relates to a new and improved leaf flipper for use with loose leaf binders and is particularly well adapted for use with the types of binders known as 5 split ring or prong binders.

In the use of loose leaf binders of the type in which the loose leaves are secured in the binder by means of split rings or prongs which extend through perforations in the 10 leaves it is necessary during such use that the leaves be moved on the rings or prongs.

For example, when such a binder is open and it is desired to close it the covers, as they are brought together, will carry the leaves 15 with them and will move the leaves upwardly on the rings or prongs. When this movement takes place the outer ends of the leaves will be moved upwardly in advance of the inner ends of the sheets which carry the 20 perforations with the result that the perforations in the sheets will be placed in an oblique relation to the rings or prongs and there will be a tendency for the sheets to bind on the rings or prongs during their movement on 25 them. When this takes place there is great liability of injury to the sheets and particularly to the bottom sheets which support the weight of the sheets which are positioned on top of them, and the main object of my invention is to provide a device which will protect 30 the sheets in a loose leaf binder when they are being moved on the rings or prongs of the binder.

Another object is to provide a protective 35 device of such a character that it will act as a guide for the leaves during such movement.

Another object is to provide a device of the character described which will be of such a design that its own movement on the rings 40 or prongs of a binder will be accomplished easily without any tendency for the device to bind on the rings or prongs during such movement.

Other objects and advantages relate to the 45 size, shape and association of the different parts of my device all as will more fully appear from the following description taken in connection with the accompanying drawings, in which:

50 Figure 1 is a perspective view of my device.

Figure 2 is a top plan view partially broken away and partially in section of a loose leaf binder in the open position with two of my devices in position on the same.

55 Figure 3 is a section on line 3—3 of Figure

2 showing the covers of the device in the partially closed position, drawn on a larger scale.

For the purpose of explaining the construction of my device and the way in which it is used with a loose leaf binder I have here 60 shown a binder of the type which is usually called a split ring binder. The binder here shown consists of a back member 1 to which are connected opposed covers 2 and 3 by means of flexible hinges 4 and 5 respectively. 65

A spring back plate 6 curved in cross section is secured to the back 1 by rivets or other convenient means, not shown. Spring plate 6 has its longitudinal edges return bent to form channels 7 and 8. A toggle plate 9, having secured to its upper surface a plurality, in this case shown as five, of half rings 10 in spaced relation, is positioned with its outer longitudinal edge in channel 8 and with its inner longitudinal edge positioned between 70 the heads of double headed buttons 11, one only being shown. A second toggle plate 12, having secured thereto a plurality, in this case shown as five, of half rings 13 in spaced relation, is positioned with its outer longitudinal edge in channel 7 and with its inner longitudinal edge between the heads of buttons 11. A curved cover plate 19, having its opposite longitudinal edge return bent, is placed in position above spring plate 6 with 75 its longitudinal edges in engagement with the longitudinal edges of spring plate 6, the resiliency of spring plate 6 and cover plate 19 retaining the parts in this position. Cover plate 19 is provided with a plurality of slots 80 20 and 21 in registration with half rings 10 and 13 to permit the movement therethrough of half rings 10 and 13 when they are moved towards and from each other in the manner about to be described. The combined width 85 of toggle plates 9 and 12 is slightly greater than the distance between channels 7 and 8 so that when the inner edges of toggle plates 9 and 12 are raised upwardly to separate half rings 10 and 13 such movement will be ac- 90 complished against the pressure of spring plate 6 so that when the inner edges of such toggle plates 9 and 12 have been raised above channels 7 and 8 the pressure of spring plate 6 on the outer edges of toggle plates 9 and 12 95 will resist any downward movement of the inner edges of toggle plates 9 and 12 and will yieldingly hold half rings 10 and 13 in the open position. Similarly when the inner edges of toggle plates 9 and 12 are moved 100

105 Figure 3 is a section on line 3—3 of Figure 110

downwardly for the purpose of joining together the ends of half rings 10 and 13 such movement will be accomplished against the pressure of spring plate 6 and when the inner edges of toggle plates 9 and 12 have been moved below channels 7 and 8 and half rings 10 and 13 brought together the pressure of spring plate 6 will resist any upward movement of the inner edges of toggle plates 9 and 12 to yieldingly hold the half rings 10 and 13 in the closed position. The upward and also the downward movement of the inner edges of toggle plates 9 and 12 is limited due to the fact that the distance between the heads 10 of buttons 11 is such that only a limited movement of the edges of toggle plates 9 and 12 therebetween is permitted.

The half rings 10 on toggle plate 9 are so positioned with relation to the half rings 13 20 on toggle plate 12 that when opposing half rings are moved towards each other their upper ends will register with each other.

The device which I provide for use with a loose leaf binder of the type just described 25 consists of an approximately rectangular member 14 preferably made of metal or fibre or some other material sufficiently stiff so that the device will not become malformed during use. I provide in member 14 a plurality, in this case shown as five, of oval apertures 15 so positioned that they will register with the rings 10 and 13 of the binder. I also provide in the edge of the member 14 opposite the apertures 15 notches 30 35 16 for a purpose hereinafter to be described. The material of which member 14 is made adjacent the inner ends of apertures 15, is displaced to form a U-shaped groove or channel 17 extending downwardly from the upper 40 surface of member 14 to apertures 15.

The material between the apertures and the adjacent notches 16 is displaced upwardly to form a reverse groove 18 connecting apertures 15 and adjacent notches 16.

In operation, I place one of my members 45 14 in position on cover 3 with half rings 10 extending upwardly through apertures 15. I place another member 14 on cover 2 with half rings 13 extending upwardly through 50 apertures 15. This relation of parts is shown in Figure 2 and indicated by dotted lines in Figure 3. When covers 2 and 3 are moved upwardly from the open position shown in dotted lines in Figure 3 they will carry upwardly the outer edges of members 14 positioned on them which will cause the inner edges of members 14 to contact with cover plate 19 and move outwardly thereupon. This upward movement of members 14 will 55 cause the grooves 18 to contact with the inner faces of half rings 10 and 13 and will also cause the grooves 17 to contact with the outer surface of half rings 10 and 13. The shape 60 of grooves 17 and 18 and their position in

relation to apertures 15 is such that members 65 14 may be moved upwardly along half rings 10 and 13 with no tendency to bind thereon as would be the case if grooves 17 and 18 were not provided.

Notches 16 are provided so that when the 70 inner edges of members 14 have moved outwardly to half rings 10 and 13, half rings 10 and 13 will enter notches 16 to permit the further outward movement of the inner edges of members 14 and permit the apertures 15 75 to continue in their proper position in relation to half rings 10 and 13.

Altho I have not here shown any leaves in position in the binder it will be obvious that 80 in actual operation with leaves in a binder the members 14 during the closing of the binder will act as a supporting and guiding means for the leaves in position thereon inasmuch as their path of movement along half rings 10 and 13 will be the same as the path of movement which the leaves will follow during 85 their movement along half rings 10 and 13.

It will be understood that the size and shape of my device may be varied to accommodate it to different sizes and shapes of loose 90 leaf binders and it will also be understood that the number and relative position of apertures 15 and notches 16 may also be varied depending upon the type of binder with 95 which my device is to be utilized, for altho I have shown and described a specific structure and form and relation of parts as an exemplification of an embodiment of my invention I do not desire to restrict myself to the exact size, shape or relation of parts as 100 various changes may be made within the scope of the appended claims.

I claim:

1. In a device of the class described, a body, a plurality of apertures in spaced relation adjacent one longitudinal edge of the the body, notches in such longitudinal edge of the body adjacent the apertures, and reverse grooves in the body connecting the apertures and the notches.

2. In a device of the class described, a body, a plurality of apertures in spaced relation adjacent one longitudinal edge of the body, notches in such longitudinal edge of the body adjacent the apertures, and channels in the body adjacent the inner ends of the apertures.

3. In a device of the class described, a body, a plurality of apertures in spaced relation adjacent one longitudinal edge of the body, notches in such longitudinal edge of the body adjacent the apertures, reverse grooves in the body connecting the apertures and the notches, and channels in the body adjacent the inner ends of the apertures.

In witness whereof I have hereunto set my hand this 28th day of September, 1928.

PAUL O. UNGER.
